UNITED STATES PATENT OFFICE.

PHILIP KLEEBERG, OF NEW YORK, N. Y.

DESIGN FOR AN EMBROIDERY-PATTERN.

SPECIFICATION forming part of Design No. 20,473, dated January 6, 1891.

Application filed December 9, 1890. Serial No. 374,084. Term of patent 3½ years.

To all whom it may concern:

Be it known that I, PHILIP KLEEBERG, a citizen of the United States, residing at New York city, in the county and State of New York, have invented and produced a new and original Design for Embroidery, of which the following is a specification, reference being had to the accompanying drawing, which represents a plan view of the design.

The design consists of a number of semi-circular connected figures *a* grouped to assimilate crescent figures *A*, and the crescent

figures are represented as united, producing the effect of a festoon by cylindrical figures *b*, from the top of which curved horn-like figures *b'* extend in opposite directions.

I claim—

A design for embroidery, substantially as shown and described.

PHILIP KLEEBERG.
